John H. Gaumer,
His Attorney.

UNITED STATES PATENT OFFICE

ADOLPH RUBIN, OF ST. LOUIS, MISSOURI

REFRIGERATOR LATCH

Application filed January 21, 1929. Serial No. 333,764.

This invention relates to latches for refrigerator doors.

In the ordinary latch for refrigerator doors, the bolt must strike the bevel portion 5 of the keeper in order to place it in position to snap behind the catch and keep the door in position. This causes a strain on the latch, its parts and fastenings.

An object, therefore, of this invention is to 10 provide a latch in which the bolt, after the door is opened, will be held in withdrawn position until the door is closed; in which the latch is simple of construction, economical to manufacture, positive in operation, durable 15 in use, and easy of repair.

Other objects will appear from the following description taken in connection with the accompanying drawings, in which:

Fig. 1 is a plan view of the latch with its 20 keepers;

Fig. 2 is a sectional view taken on lines 2—2, Fig. 1;

Fig. 3 is a rear elevation, with the bolt shown in withdrawn position;

Fig. 4 is a sectional view on line 4—4, Fig. 2.

The base of the latch may be of any preferred shape, but, as illustrated, may consist of the hollow casing 1, with attaching flanges 2, and upstanding ears 3 to support the latch- 30 ing element.

The latching element consists of the handle 4, sleeve 5, arm 6, bolt 7, and the trigger engaging pin 8. This element is preferably made integral, and may be cast in one piece. The latching element is pivotally mounted 35 between the ears 3 upon a pin 9. One end of the sleeve 5 is adapted to fit the pin 9, and the other end the flanged bushing 10. One 40 end of the tension spring 11 is in engagement with the flanged bushing 10 and the other end is in engagement with the sleeve 5. The bushing 10 has in the periphery of its flange one, or preferably more, holes 12 adapted to receive the stud 13. The pin 9 may be secured 45 in position by any appropriate means such as the cotter pin 14.

Inside the casing on the pin 15 is mounted 50 the trigger element consisting of the lever 16, bearing 17, arm 18, having recess 19, and

the projection 20. The stud 13 bears upon the lever 16.

The keeper comprises the attaching flanges 21, the usual notched and beveled ear 22, and the abutment 23 adapted to engage the trigger projection 20. 55

In operation, with the latch in the position shown in Fig. 1, an upward movement of the handle moves the bolt out of engagement with its keeper, causing the trigger-engaging 60 pin 8 to be held in the recess 19 on the arm 18, by reason of the action of the spring 11 acting on the trigger through the flanged bushing 10 and stud 13. When the door is closed, the trigger projection 20 strikes the keeper abutment 23 releasing the bolt, which by reason of the action of the spring 11 bearing 65 on the sleeve, is forced within the keeper.

The tension of the spring 11 may be adjusted by placing the stud in the different 70 holes 13.

A latch of the construction illustrated and described is of simple and rugged construction, may be economically manufactured, is 75 durable, positive in operation, and may be readily dismantled for repair; thus accomplishing its purposes.

It is to be understood that various changes may be made in the details of construction, within the scope of the appended claims, 80 without departing from the spirit of this invention.

Having thus described the invention, what is claimed is:

1. A refrigerator door latch comprising, 85 a base, a handle pivotally mounted on said base for rotation in a plane transverse of the door, a bolt integral with said handle adapted to cooperate with a keeper, a spring to actuate the bolt, and a trigger adapted to engage the bolt and hold it in an inoperative position after it has been disengaged from the keeper.

2. A refrigerator door latch comprising, 90 a housing, a pin mounted on said housing parallel to the door, a handle pivotally mounted on the pin, a bolt integral with said handle adapted to cooperate with a keeper, a torsion spring about said pin adapted to actuate the bolt, and a trigger adapted to engage 95 the bolt and hold it in an inoperative position 100.

- position after it has been disengaged from the keeper.
3. A refrigerator door latch comprising, a housing, a pin mounted on said housing, a handle pivotally mounted on the pin, a bolt integral with said handle adapted to cooperate with a keeper, a torsion spring about said pin adapted to actuate the bolt, a trigger adapted to engage the bolt and hold it in an inoperative position after it has been disengaged from the keeper, and a flanged bushing on said pin and a stud in the periphery of said flange adapted to bear against the trigger.
- 15 4. A refrigerator door latch comprising, a housing, a pin mounted on said housing, a handle pivotally mounted on the pin, a bolt integral with said handle adapted to cooperate with a keeper, a torsion spring about said pin adapted to actuate the bolt, a trigger adapted to engage the bolt and hold it in inoperative position after it has been disengaged from the keeper, a flanged bushing on said pin, a stud in the periphery of said flange adapted to bear against the trigger, and means for adjusting the tension of the spring, comprising spaced holes in the periphery of the flange for inserting said stud in different positions on the flange.
- 25 5. A refrigerator door latch comprising, a base, a handle pivotally mounted on said base for rotation in a plane transverse of the door, a bolt mounted for rotation about the same axis as the handle and adapted to cooperate with a keeper, a spring to actuate the bolt, and a trigger pivotally mounted in the housing and having a recess therein adapted to engage the bolt and hold it in inoperative position after it has been disengaged from the keeper.
- 30 6. A refrigerator door latch comprising, a base, a pin mounted on said base pivotally supporting a latching element comprising, integrally a handle, a sleeve to engage said pin, an arm and a bolt on the arm to engage a keeper; a torsion spring about said pin and within said sleeve, engaging one end of the sleeve to move the latching element, and a bushing to engage the other end of the spring and means to adjustably secure said bushing.
- 35 7. A refrigerator door latch comprising, a base, a pin mounted on said base pivotally supporting a latching element comprising, integrally a handle, a sleeve to engage said pin, an arm and a bolt on the arm to engage a keeper; a torsion spring about said pin and within said sleeve, engaging one end of the sleeve to move the latching element, and means to adjustably secure the other end of said spring.
- 40 8. A refrigerator door latch comprising, a base, a pin mounted on said base pivotally supporting a latching element comprising, integrally a handle, a sleeve to engage said pin, an arm and a bolt on the arm to engage a keeper; a torsion spring about said pin and within said sleeve, engaging one end of the sleeve to move the latching element, and a stud in one of said holes to retain the tension of said spring.
- 45 9. A refrigerator door latch comprising, a base, a pin mounted on said base, pivotally supporting a latching element comprising integrally a handle, a sleeve to engage said pin, an arm, a trigger engaging pin and a bolt adapted to engage a keeper; a trigger element pivotally mounted in said base comprising a lever and a recessed arm having a projection adapted to engage a lug on the keeper; a flanged bushing on said pin; a torsion spring about said pin and within said sleeve engaging one end of said sleeve and said bushing; and holes in the periphery of the bushing adapted to receive a stud to bear against the trigger arm; for the purpose described.
- 50 In testimony whereof I affix my signature this 22nd day of August, 1928.
